UNITED STATES PATENT OFFICE.

AURIN E. PAYSON, OF NORWICH, CONNECTICUT.

DESIGN FOR A TEMPERATURE-RETAINING RECEPTACLE.

Application filed April 25, 1928. Serial No. 26,451. Term of patent 14 years.

To all whom it may concern:

Be it known that I, AURIN E. PAYSON, a citizen of the United States, residing at Norwich, Connecticut, in the county of New London and State of Connecticut, have invented a new, original, and ornamental Design for Temperature-Retaining Receptacles, of which the following is a specification, reference being had to the accompanying drawing, forming part thereof.

Fig. 1 is a side view of a temperature-retaining receptacle showing my new design;

Fig. 2 is a plan in section on line 2—2 of Fig. 1, and

Fig. 3 is a fragmentary showing of the lower portion of the receptacle illustrating one of the Eskimo figures in side elevation.

I claim:

The ornamental design for a temperature-retaining receptacle, as shown.

AURIN E. PAYSON.
